UNITED STATES PATENT OFFICE

JAMES B. DUNN, OF NEW ORLEANS, LOUISIANA.

FURNACE FOR BURNING BAGASSE.

SPECIFICATION forming part of Letters Patent No. 364,228, dated June 7, 1887.

Application filed March 22, 1887. Serial No. 231,960. (No model.)

To all whom it may concern:

Be it known that I, JAMES B. DUNN, of New Orleans, Louisiana, have invented certain new and useful Improvements in Furnaces for Burning Bagasse and other Green Fuel, of which the following is a specification:

My invention consists, primarily, of a plan for setting boilers for utilizing bagasse, saw-dust, or other green fuel under the boilers; and in carrying out my invention I employ a furnace without grate-bars, but having tuyeres and a suitable blower or artificial blast, and locate the furnace immediately beneath the boilers. Furnaces having tuyeres and blast apparatus have been constructed to burn bagasse without grate-bars; but such furnaces have invariably been located at one side or at one end of the boilers and the gases or products of combustion passed through a heating-chamber, or "mixing-chamber," as it is more commonly called, before coming in contact with the boilers. The theory has been that the different gases or vapors generated by the products of combustion had to be heated or mixed in an intermediate chamber in order to produce any economical practical results. I have discovered that the mixing chamber or passage between the furnace and boiler is superfluous, and that better results may be obtained by setting the blast-furnace without grate-bars immediately beneath the boilers, as in my improved plan.

My invention also contemplates certain important improvements in structural arrangement and details, all of which will be understood from the following description.

In the accompanying drawings, Figure 1 is a longitudinal vertical section on the line 1 1 of Fig. 2; Fig. 2, a transverse section on the line 2 2 of Fig. 1; and Fig. 3, a horizontal section showing the ground plan on the line 3 3 of Fig. 1.

X represents a brick foundation upon which the boilers are set.

In the drawings I have illustrated four boilers, Y, of any suitable size—say thirty feet long and forty-two inches in diameter—each having two flues, y, about sixteen inches in diameter. Any other horizontal boilers, whether flue or cylinder boilers, may, however, be used. They are mounted in well-known ways at front and rear in the brick-work.

The furnace A, which is without grate-bars, has a closed hearth, and is provided with suitable tuyeres and blast apparatus, is located 55 immediately under the front of the boilers, being arranged transversely thereunder.

B B represent ordinary ash-doors at the opposite ends of the furnace. In the walls surrounding the furnace are constructed blast-chambers D, which are kept filled with compressed air by pipes D', communicating with a suitable power-driven blower, D². Tuyeres C extend from the blast-chambers to the interior of the furnace, and are preferably arranged 65 as seen in Fig. 2—that is, the tuyeres are arranged in a solid bank nearest the bottom of the furnace; but commencing with, say, the fourth or fifth row, they are arranged in two pyramidal forms on each side of the furnace, 70 for a purpose presently described.

In the front wall of the furnace a number of taps or pipes, E, are provided, one opposite each tuyere C. These taps are normally closed by suitable plugs or caps, which may be removed for the insertion of cleaning-rods, which may be passed through each opening and through the tuyere opposite it, to clean out and keep the tuyeres open.

At the rear of the furnace a transverse passage-way, F, is formed in the masonry of the furnace, and in the wall of this passage are similar openings, E, opposite the tuyeres C. The passage F is made sufficiently large to permit a workman to enter for the purpose of 80 cleaning out the tuyeres on that side of the furnace. One or more doors, A', may be provided in the end and side walls of the furnace for the purpose of introducing wood or coal, should it be desired to use such fuel. The products 90 of combustion pass up into contact with the boilers and over the arch G, formed by the masonry covering the transverse passage F. At one or both sides of the flat top g of this arch are arranged doors H, for the removal of 95 any ashes that may accumulate thereon. At the rear of the arch G is a chamber, L, in which ashes carried over by the draft will be deposited, and in each side of this chamber are provided doors I, for the removal of the ashes. 100

K represents the brick foundation for the ordinary mud-drum, M, upon which the rear ends of the boilers are in this instance supported.

N represents a bridge-wall under the rear ends of the boilers, to regulate the quantity of heat to be let into the boiler-flues, while n indicates a space left between the ends of the 5 boilers and the end wall of the masonry. A small door, O, may be provided at this end of the furnace, through which the flames returning into the boiler-flues may be observed. The tops of the boilers and the spaces between 10 them and between the outside boilers and the masonry are protected by a jacket or cover, P, as seen more especially in Fig. 2. The flames from the furnace will pass the entire length of the boiler in contact therewith, and then 15 through the boiler-flues, should flued boilers be used, to the chimney W.

The bagasse or green fuel may be fed to the furnace by means of an endless belt, Q, which delivers the fuel into a hopper having a bottom 20 of an inverted-V shape in cross-section, so that the fuel is divided about equally as delivered to the hopper, one portion passing through a feeding-aperture, S, between the two right-hand boilers over one end of the furnace, 25 and the other to a similar aperture between the two left-hand boilers over the opposite end of the furnace. The pyramidal arrangement of the tuyeres before mentioned is made with reference to these feeding-apertures—that is, 30 the apexes of the pyramids of tuyeres are arranged in line with the feeders.

When the bagasse or other wet fuel falls from the feeder or hopper, the greatest number of tuyeres will act upon it in the line of 35 feed where the greatest mass of fuel is to be operated upon, and by arranging the tuyeres in a pyramidal form the fuel which tends to accumulate on the hearth in pyramidal piles will be acted upon at different points in proportion 40 to the mass of the fuel. I thus avoid the unnecessary introduction of air into the furnace at points where it is not needed.

T indicates an ordinary steam-drum arranged transversely above the boilers.

45 In each feed chute or aperture is arranged a valve or damper, which is normally kept closed by a weighted projecting arm, s. An accumulation of fuel sufficient to overcome the gravity of the valve depresses it and admits the fuel to the furnace.

In the organization described it will be perceived that the furnace is located directly beneath the front ends of the boilers, and that the flames or products of combustion rise from 55 the furnace immediately against the boilers and travel their entire length in contact with them. I have found that with such a construction better results are obtained than with the old plan of providing a mixing or heating 60 chamber for the products of combustion. The structure is very much simpler and less expensive than the old plan, as the arrangement is more compact, the necessary amount of masonry very much reduced, and the brick-work 65 passage or mixing-chamber between the furnace and boiler is dispensed with.

My improved organization possesses the

very important advantage, among other things, that by increasing the length of the furnace additional boilers may be arranged in the nest 70 and additional feeding-apertures may be provided between the boilers. For instance, by doubling the width of the plant as viewed in cross-section in Fig. 2, four additional boilers may be employed, in which event I prefer to 75 provide two additional feeding-apertures and have four pyramids of tuyeres on each side of the furnace.

In establishing a plant the furnace A might be made of sufficient length to accommodate 80 more boilers than are actually needed, and then additional boilers could be added should occasion require.

The fact of being able to heat a number of 85 boilers from the same furnace is, I repeat, an important matter, and one which will be readily appreciated when it is understood. Where the furnace is located to one side of the boilers, only about three boilers to each furnace can be employed with advantage.

With the particular organization illustrated 90 the tuyeres may be cleaned from time to time, whenever desired, without in any manner interrupting the working of the furnace. This is a very important matter, and results in great 95 economy in time, labor, and fuel.

The tuyeres, as will be perceived from Fig. 3, are preferably tapering, being widest at the blast-chambers. The size of the tuyeres where they open into the furnace may be, say, three-fourths of an inch in diameter. I prefer to make them of such a size that they will be sufficient to throw the blast well into the center of the furnace without injecting an unnecessary amount of cold air.

I am aware that furnaces having ordinary 100 grate-bars, or perforated hearths, or arched skeleton hearths operating after the manner of grate-bar furnaces, have been placed under boilers, and that it has been attempted to burn green fuel in them. I do not claim any such 105 subject-matter.

I claim as my invention—

1. In a furnace for burning bagasse and other like fuel, the combination of the frame 110 or masonry, a nest of boilers mounted therein, and a furnace, A, arranged transversely immediately beneath the boilers, said furnace being without grate-bars, but having tuyeres and suitable blast apparatus, substantially as 115 and for the purpose set forth.

2. In a furnace for burning bagasse and other like fuel, the combination of the frame or masonry, a nest of boilers mounted therein in substantially the same horizontal plane, a 120 furnace having a length in excess of its width, arranged transversely immediately beneath the boilers, said furnace being without grate-bars, but having tuyeres and suitable blast apparatus, and feeding chutes or apertures arranged to deliver the green fuel between the 125 boilers and into the furnace at different points, substantially as and for the purpose set forth.

3. In a furnace for burning bagasse and

other like fuel, the combination of the frame or masonry, the boilers mounted therein, a furnace without grate-bars arranged immediately beneath the boilers, a feed-chute for delivering the green fuel into the furnace, tuyeres in the wall of the furnace, arranged in a pyramidal form in line with the fall of the fuel-supply, and suitable blast apparatus for injecting air through the tuyeres, substantially as and for the purpose set forth.

4. In a furnace for burning bagasse and other like fuel, the combination of the frame or masonry, a nest of boilers mounted therein in substantially the same horizontal plane, a furnace without grate-bars arranged immediately beneath the boiler, two or more feed-chutes for delivering the green fuel into the furnace at different points, tuyeres in the opposite wall arranged on each side in pyramidal form in line with the feed, and suitable blast apparatus, substantially as and for the purpose set forth.

5. In a furnace for burning bagasse and other like fuel, the combination of the frame or masonry, a nest of boilers mounted therein, a feed-hopper having an inverted-V-shaped bottom, and feed-chutes to which the green fuel delivered to the hopper is directed by the inclined sides of the hopper-bottom, the chutes being arranged to deliver the feed between pairs of boilers, the furnace A, without grate-bars and having tuyeres, and suitable blast apparatus arranged immediately beneath the boilers, substantially as and for the purpose set forth.

35 6. The combination of the furnace A, a blast-chamber formed in the wall thereof, tuyeres leading from the blast-chamber into the furnace, and taps or cleaning-apertures extending 40 from the outer wall of the furnace to the blast-chamber, each of said taps being arranged in

line with a tuyere, whereby the tuyeres may be cleaned without slowing down the furnace.

7. The combination of the furnace A, the blast-chamber in the wall thereof, the tuyeres 45 leading from the blast-chamber to the furnace, the transverse passage-way F, and taps or openings in the walls of said passage-way, each tap being arranged opposite a tuyere in the furnace-wall, whereby the tuyeres on that side 50 of the furnace may be cleaned without slowing down the fire, substantially as and for the purpose set forth.

8. The combination of the furnace, the blast-chamber formed in the wall thereof, the conically-shaped tuyeres having their largest opening next the blast-furnace, and the cleaning taps or apertures extending from the opposite wall of the blast-chamber to the exterior of the furnace, substantially as and for the purpose 60 set forth.

9. The combination of the frame or masonry, the nest of flue-boilers mounted therein, the furnace A, without grate-bars and having tuyeres, a suitable blast apparatus arranged 65 immediately under the boilers, the masonry arch in which the transverse passage is arranged, the blast-furnace, and tuyere-cleaning openings in the walls of the furnace, the ash-receptacle in the rear of the arch, doors for 70 withdrawing the ashes from the receptacle, the mud-drum and its support arranged in rear of the ash-chamber, and fuel-feeding devices for supplying the green fuel to the furnace at more than one point.

In testimony whereof I have hereunto subscribed my name.

JAMES B. DUNN.
